CLAIM

The ornamental design for a pestle, as shown and described.

DESCRIPTION

FIG. 1 is a right side view of a pestle;

FIG. 2 is a left side view of the pestle of FIG. 1;

FIG. 3 is a perspective view of the pestle of FIG. 1;

FIG. 4 a bottom plan view of the pestle of FIG. 1;

FIG. 5 is a top plan view of the pestle of FIG. 1; and,

FIG. 6 is an additional right side view of the pestle of FIG. 1.

In FIG. 6, the broken lines are for the purpose of illustrating environment only and form no part of the claimed design.
